UNITED STATES PATENT OFFICE.

EDWARD M. POONS, OF NEW YORK, N. Y.

SWEATBAND FOR HATS.

Application filed August 17, 1926. Serial No. 129,808.

My invention relates to sweat bands for hats and has for an object to provide a band which is serviceable, light in weight, and attractive.

Another object is to provide a sweat band which is impervious to moisture, and has both horizontal and vertical air passages for purposes of ventilation.

Another object is to provide a sweat band composed of tubular material formed into superimposed annular layers secured together.

Another object is to provide a sweat band composed of a plurality of annular bands assembled concentrically in spaced relation, thereby providing vertical channels for the passage of air therethrough.

A practical embodiment of my invention is represented in the accompanying drawings in which

Fig. 1 represents a detail inverted plane view of a portion of a hat having my improved sweat band inserted therein;

Fig. 2 represents a detail vertical section taken in the plane of the line II—II of Fig. 1 looking in the direction of the arrows;

Fig. 3 represents a plan view of my improved sweat band;

Fig. 4 represents a side elevation of the same partly in section;

Fig. 5 represents a plan view of a modified form of sweat band; and

Fig. 6 represents a side elevation of the same partly in section, a portion of which is broken away.

In Figs. 1 and 2 the portion of the hat shown is denoted by 1* and my improved sweat band is secured therein by any well known or approved means.

In the form shown in Figs. 1 to 4 inclusive, I have illustrated a sweat band composed of an inner band denoted by 1, an upper outer band by 2, a lower outer band by 3 and an intermediate band by 4. The intermediate band 4 is disposed concentrically around the inner band 1, while the outer bands 2, 3, are located concentrically upon the intermediate band. The bands are tapered so as to conform substantially to the head of the wearer. Each of the bands is formed of a strand or strands 5 of tubular material, such as straw, superimposed in annular layers and secured together in any well-known and approved manner. In the present instance, I have shown the annular

layers forming each band as secured by thread 6.

The inner band 1 is spaced from the outer bands 2, 3, by the intermediate band 4 which is bent at intervals into zigzag formation, 60 the inner apices of the bends of each band being secured at 7 to the inner band 1 while the outer apices of the bends are fixed to the upper outer band at 8 and to the lower outer band at 9.

Thus it will be seen that a series of vertically disposed channels 10 will be located between the inner band 1 and the intermediate band 4, and short upper and lower vertically disposed channels 11, 12, between the intermediate band 4 and the upper and lower bands 2, 3, respectively.

Channels 11, 12, merge into open chambers 13 formed by the zigzag formation of the intermediate band 4 and between the upper and lower outer bands 2, 3.

A band formed by my improved structure, when inserted in a hat, provides efficient ventilation to the head of the wearer through the vertically disposed channels and by reason of the tubular material, such as straw, small horizontally disposed open channels are formed between the adjacent annular layers of the material, which contact with the wearer.

It is to be understood that while I have shown each band formed of continuous strand of tubular material formed into superimposed layers, each band may be formed of a plurality of strands of tubular material, each strand fixed into a separate annular layer and each layer superimposed and secured to the adjacent layer.

In the form shown in Figs. 5 and 6, I have illustrated a sweat band 14 composed of superimposed annular layers of tubular material, in which band the means 15 of securing the layers is passed vertically through the center of each of the layers and to the outside of the band, so as to present a substantially smooth or unbroken surface to the head of the wearer.

It is obvious that various changes may be resorted to in the form, construction and arrangement of the bands without departing from the spirit and scope of my invention; and hence I do not wish to be limited to the details herein shown and described, except as they may be included in the claims.

What I claim is:

- 2
1. A sweat band for hats comprising a series of endless bands of material concentrically disposed and secured together, each of said bands being composed of a continuous strand of tubular material formed into superimposed annular layers secured together in substantially horizontal alinement. 35
2. A sweat band for hats comprising a series of endless bands of material concentrically disposed and secured together in spaced relation, each of said bands being composed of a continuous strand of tubular material formed into superimposed annular layers secured together in substantially horizontal alinement. 40
3. A sweat band for hats comprising a series of endless bands concentrically disposed and secured together, each of said bands being composed of a continuous 45 strand of straw formed into superimposed annular layers secured together in substantially horizontal alinement.
4. A sweat band for hats comprising a series of endless bands concentrically disposed and secured together in spaced relation, each of said bands being composed of a continuous strand of straw formed into superimposed annular layers secured together in substantially horizontal alinement. 50
5. A sweat band for hats comprising a series of endless bands concentrically disposed and secured together, each of said bands being composed of a continuous strand of straw formed into superimposed annular layers secured together in substantially horizontal alinement. 55
6. A sweat band for hats comprising a series of endless bands concentrically disposed and secured together in spaced relation, each of said bands being composed of a continuous strand of straw formed into superimposed annular layers secured together in substantially horizontal alinement, certain of said bands being of zigzag formation.
7. A sweat band for hats comprising inner and outer endless bands concentrically disposed, and an endless band of zigzag formation interposed between said inner and outer bands and secured to the bands at the adjacent points of contact with the bands, each of said bands being composed of strands of straw formed into superimposed annular layers secured together. 60

In testimony, that I claim the foregoing as my invention, I have signed my name this 12th day of August, 1926.

EDWARD M. POONS.
